UNITED STATES PATENT OFFICE.

LEONARD NUTZ, OF SPRINGFIELD, MISSOURI, ASSIGNOR OF ONE-HALF TO
W. W. DONHAM, OF SAME PLACE.

STOVE.

SPECIFICATION forming part of Letters Patent No. 546,026, dated September 10, 1895.

Application filed October 8, 1894. Serial No. 525,274. (No model.)

To all whom it may concern:

Be it known that I, LEONARD NUTZ, a citizen of the United States, residing at Springfield, in the county of Greene and State of Missouri, have invented a new and useful 5 Stove, of which the following is a specification.

The invention relates to improvements in stoves.

The object of the present invention is to 10 improve the construction of stoves to economize fuel and to provide a damper attachment capable of enabling the draft to be readily controlled and adapted to hold a body of fire a great length of time, and thereby save fuel.

15 The invention consists in the construction and novel combination and arrangement of parts hereinafter fully described, illustrated in the accompanying drawings, and pointed out in the claim hereto appended.

20 In the drawings, Figure 1 is a perspective view of a stove constructed in accordance with this invention. Fig. 2 is a vertical sectional view of the damper attachment. Fig. 3 is a transverse sectional view of the same.

25 Like numerals of reference indicate like parts in all the figures of the drawings.

1 designates a wood stove or heater of any 30 desired configuration and provided at its front with upper draft-openings 2 and a lower enlarged opening 3, which openings are covered by a damper-casing 4, and admission of air into the stove is controlled by a vertically-movable damper 5. The lower opening 3 is of a size to permit the entrance of a fire-shovel 35 for the purpose of removing ashes. The casing 4, which prevents side drafts from choking the fire when the shovel-opening 3 is exposed, is substantially rectangular, and is composed of similar outward-extending sides 6, a horizontal top 7, and a bottom 8, extending horizontally beyond the sides to form a hearth-platform and provided at its edges with a vertical flange 9 to prevent ashes from spilling upon the floor. The sides 6 are provided at their 40 edges with vertical ways 10, in which the damper 5 is slidingly mounted and is adapted to be raised to expose the shovel-opening and to permit a draft. The damper may be provided with a central opening and may have secured 45 therein a piece of isinglass 11; but a solid dam-

per may be employed, if desired. It is raised and lowered by means of a vertically-disposed rod 12, rising centrally from the top of the damper and arranged in a perforation of a guide-arm 13 and frictionally engaging the latter and terminating in a knob or handle 14. The lower portion of the rod is secured to the back or inner face of the projecting upper portion of the damper, and the latter is provided on its inner or rear face with a horizontal flange 15, 55 adapted to abut against the top of the casing to form a stop. The damper may be raised to a greater or less extent to obtain the desired draft, and the draft may be entirely shut off to hold a body of fire for a long time for the 60 purpose of economizing fuel.

The casing may be of any desired size and shape, and it provides an intervening air-space to prevent the heat of the stove from warping or otherwise injuring the damper; 70 and although in the accompanying drawings the damper attachment is shown applied to a wood-stove it will be readily understood that it may be employed on any ordinary form of heating-stove.

75 It will be seen that the damper attachment is simple and comparatively inexpensive in construction, that it enables the draft to be readily controlled, and that it is capable of lessening the expenditure of fuel. It will also 80 be seen that the damper is protected from excessive heat, that it is adapted to expose the shovel-opening, and that the casing prevents ashes and coals from dropping upon the floor.

85 Changes in the form, proportion, and the minor details of construction may be resorted to without departing from the principle or sacrificing any of the advantages of this invention.

90 What I claim is—

The combination with a stove provided at its front with openings, one of them being enlarged to permit the insertion of a shovel, and a guide arm extending horizontally from the 95 top of the stove and provided with a perforation, of a casing mounted on the stove and covering the openings, and comprising vertical sides provided with ways, a top connecting the upper ends of the sides, and a bottom, and 100

a vertically movable damper mounted in said ways and closing the front of the casing and provided with an upward extending operating rod arranged in the perforation of the guide arm and frictionally engaging the latter, whereby it is secured at the desired adjustment, substantially as described.

In testimony that I claim the foregoing as my own I have hereto affixed my signature in the presence of two witnesses.

LEONARD NUTZ.
